DISPLAY

Stanley Joseloff, Westport, Conn.

Application November 16, 1954, Serial No. 469,109

1 Claim. (Cl. 40—28.1)

This invention relates generally to display devices, and more particularly to such having structure suitable for multiple purposes.

With the growth of self-service merchandising, as for example, of the "super-market" type, large areas of selling floor space are not attended by store personnel. This puts upon the patron the burden of locating different articles, and it therefore becomes desirable to provide means which is easily visible, and which enables the patron to direct himself to a particular sales counter, display or island. It is therefore among the principal objects of the present invention to provide structure for these purposes.

Because it frequently becomes necessary to change store traffic pattern and consequently location of merchandising, flexibility is important, and it is another object of the present invention to provide structure whereby the indicia for identifying the merchandise is readily changed. On occasion, it may be desirable to substitute for written material indicating the adjacent merchandise, a physical representation or example of the items being sold thereat, and the present structure affords opportunity for this as well.

Another object herein lies in the provision of structure of the class described, which affords independent illumination so that the same may be independently controlled so as to be useful, not only for making the indicia more readily visible, but also so that the lighting may be used as emergency lighting, or night lights, when the major illumination of the establishment is extinguished.

In present merchandising methods, it is desirable to provide music and spot announcements for point of sale advertising, and it is another object herein to provide structure which will properly direct the sound having a high degree of intelligibility to the patron adjacent the merchandise locations. A feature herein lies in the fact that the speaker elements producing such sound, while easily aimed and baffled, are relatively inconspicuous and protected from dust and dirt.

As mentioned above, since large areas are devoid of personal surveillance, it is another object of the invention to provide means for detecting theft and pilferage, and to discourage the same.

A still further object herein lies in the provision of structure of the class described, which is simple and efficient, so that the same may be manufactured in large quantities at low cost with a corresponding wide distribution and use.

A feature of the invention resides in the utility of the secondary body element which may have multiple use to accommodate to various conditions of use.

Another feature herein lies in the adjustability of the structure with respect to the central support element to adapt the same to different locations and conditions.

These objects and other incidental ends and advantages will more fully appear in the progress of this disclosure, and be pointed out in the appended claim.

2

In the drawings, in which similar reference characters designate corresponding parts throughout the several views:

5 Figure 1 is a fragmentary view in perspective showing a preferred embodiment of the invention.

Figure 2 is a fragmentary view in perspective showing one of the ways in which the device may be integrated with a merchandise island or similar display or shelf arrangement.

10 Figure 3 is a fragmentary vertical sectional view as seen from the plane 3—3 on Figure 1.

Figure 4 is a plan view of the bottom wall element and associated structure as seen from the plane 4—4 on Figure 3.

Figure 5 is a fragmentary elevational view, partially exploded, of the upper portion of the primary body element.

Figure 6 is a top plan view of the cover element.

Figure 7 is an elevational view of a second body element, and associated structure and showing an alternate form thereof.

Figure 8 is a side elevational view of Figure 7.

Figure 9 is a fragmentary view showing the lower end of one of the support arm elements as connected to the upper end of the central support element.

Figure 10 is a fragmentary perspective view of an indicia carrier member.

Figure 11 is an enlarged, fragmentary horizontal sectional view as seen from the plane 11—11 on Figure 1.

Figure 12 is a fragmentary view in perspective showing the system including one of the devices as set up, with an alternate form of camera mechanism.

Figure 13 is a perspective view showing a camera member as removed from the rest of the structure.

35 Figure 14 is a schematic electrical diagram for the system.

In accordance with the invention, the display, generally indicated by reference character 10, comprises broadly: a primary body element 12, a cover element 14, a plurality of secondary body elements 16, a plurality of support arm elements 18, a central support element 20, illumination means 22, sound producing means 24 and photographic recording means 26.

40 The primary body element preferably includes a bottom wall 28, a top wall 29 and a plurality of side walls 30. The walls 30 have large openings so that the outermost portions of said walls, at the sides thereof, may be provided with grooves 31 within which are slidably disposed glass plates 32. Such plates may be made of other light transmitting material. Permanently disposed within the primary body element is the illumination means 22, which may take any suitable form, as for example, an incandescent bulb or a fluorescent tube.

45 The top and bottom walls are preferably permanently connected to the side walls, the top wall being provided with a central orifice 34 through which the illumination means may be reached and through which the sound producing means may also be serviced when required.

50 The cover element is adapted to detachably engage within the orifice 34, and forms a closure therefor.

The primary body element is mounted upon a bracket 55 terminating at its lower portion in a union member 36.

55 The bracket serves to hold the primary body element in an elevated position in respect to the union member 36. The union member 36 may be rotatably and vertically adjusted upon the upper end 37 of the central support element 20. Means such as the set screw 38 may be used to hold the primary body element in a predetermined adjusted position with respect to the central support element 20.

The lower end 39 of the element 20 is preferably provided with a pair of juxtaposed slots 40, so that a pair of legs 41 may be formed which straddle the upright fin 42 normally disposed upon the top member 43 of a display unit 44. The legs 41 may be secured to the fin 42 by screws 144 (Figure 12) or adjustable clamping means may be there provided.

Turning now to the secondary body elements, since these are substantially identical, a detailed description of one will suffice for both. This applies as well to the support arm element 18. The secondary body element preferably comprises a vertical main plate 45 to which may be detachably secured a pair of slotted side supports 46 and 47. These have the slots downwardly converging toward the plate 45 so that the indicia carrying element 49 may be retained there by gravity with the lower edge 50 thereof abutting against the upper surface 51 of said plate 45. In view of the fact that the plate 45 is provided with a plurality of orifices, other displays may be detachably engaged therewith.

The element 49 may have secured to the front surface thereof a plurality of indicia carrying means 53 (see Figure 10) which are U-shaped in vertical section so that cards or letters may be slidably disposed therein in a well-known manner.

Certain of the said orifices 54 may be used to engage hook members 55, preferably of S-shape, which in turn engage in the orifices 56 of the cross arm 57 of the support arm element 18. The lower end 58 of the support arm element 18 is adapted to be rotatably disposed within the socket 59 which forms a part of the union member 36. By virtue of the fact that the arm 18 is radially offset a distance sufficient to adequately clear the primary body element 12, the secondary body element 16 and the support arm element 18 may be rotatably adjusted (Figure 9) to place the elements in suitable position with respect to each other.

In accordance with the invention, there is provided photographic recording means, generally indicated by reference character 26. Thus, as shown in Figures 7 and 8, the upper portions of the indicia carrying elements 49 may be altered in construction to appear as shown in Figures 7 and 8 where the indicia carrying elements 49a and 49b have secured upon the rear or inner surface thereof, the camera units 60 and 61. These are preferably of the motion picture type, including well-known shutter mechanisms for consecutively exposing individual pictures with any desired time interval between the pictures. Such cameras are well known in the motion picture art, and are therefore not described in detail. They are, however, adapted by the provision of a solenoid 62 (Figure 14) so that upon energization of the solenoid, the shutter is tripped and a single frame exposure made.

Thus, the conductors 63 and 64 may lead from a source of power (not shown) and connect with the step-down transformer 65, the secondary circuit of which includes a switch 66, as well as conductors 67 and 68 which are connected to the solenoid previously mentioned.

In Figures 12 and 13, a slightly different type of camera 60a and 60b is shown, and which is mounted on the forward surface of the upper portions of the indicia carrying elements 49c and 49d. In structure and in operation, these cameras resemble the cameras 60 and 61, except that they are more visible and have, by virtue of such display, a deterring effect against pilferage and theft.

In addition to the conductors 67 and 68 going to each individual unit 10, there are pairs of conductors 69 and 70, and 71 and 72. All of these conductors, namely, 67-72, inclusive, may be incorporated in a single sheath to form a cable in a well-known manner. Thus, the input 73 and the amplifier 74 may be located in a remote booth 75, as may also be the switch 66. Any desired number of the units 10 may be distributed about the sales area 76, 75

and interconnected so that the speakers 24 may carry announcements or music which is fed to the input 73 by the operator 80. Where desired, such intelligence may be from recordings of the tape type, records, or other types.

5 The conductors 71 and 72 may carry energy to the illumination means 22.

Thus, the device 10, in operation, carries conveniently displayed the indicia carrying elements 49, and the others corresponding thereto, which may contain permanent or temporary information concerning the products 81 which are in the display units adjacent or connected to the device 10. The support arm elements 18, as has been described, may be rotated to positions where they may be more readily seen or where they may be in a better position to take pictures of the surrounding area, as mentioned above. The illumination means 22 is adapted to cast rays outwardly through the transparent plates 32, which illumination may serve to light up the secondary body elements 16, as well as the indicia carrying elements 49. As shown in Figure 12, additional indicia 83 may be placed upon the plates 32, and such indicia will also be illuminated. The means 22 serve also as excellent night lights when all the other illumination in the store has been extinguished, and such means 22 in 25 the individual units 10 may be remotely controlled in a suitable manner.

The speakers 24 in each of the units are so constructed and arranged that the sound is directed downwardly and outwardly horizontally about 360 degrees, while the interior of the primary body element 12 serves to partially absorb the vibrations directed inwardly from the concealed surface of the speaker cone acting as an acoustic baffle, thus improving the sound quality and propagation.

35 The camera units acting as photographic recording means may, in addition to being remotely controlled, for individual exposure, be constructed and arranged to take pictures in sequence with predetermined time intervals between the pictures, thus requiring no manual control.

It may thus be seen that I have provided a novel and useful display, which by virtue of the construction and arrangement thereof, serves multiple purposes compactly and at a reasonable low cost, enabling the units to be disposed about a sales area in the number of positions required to provide adequate coverage from the viewpoint of light, sound, information disclosure, plus photographic recording.

50 The present structure is of great utility because it is very adaptable to different locations and conditions of use. The slotted side supports 46 and 47 may be removed and in their stead may be placed other display material related to the merchandise with which the device 10 is associated, or otherwise, and such materials may take the form of mobiles, pictures of personalities associated with the goods, children, bulletin boards or animated displays.

55 I wish it to be understood that I do not desire to be limited to the exact details of construction shown and described, for obvious modifications will occur to a person skilled in the art to which the present invention relates.

60 I claim:

Display unit construction adapted for use in connection with a merchandise counter comprising: a primary hollow body element having light transmitting side wall members and a bottom wall having an opening; illumination means positioned between said side walls and above said bottom wall, a sound producing means disposed upon said bottom wall and opposite said opening; a central support element having means to engage said body element, and second means for detachably connecting the same to said merchandise counter; a secondary body element, an arm element swingably connecting said second body element to said central support element proximate to and within the field of the light passing through a light transmitting side wall member, and indicia carrying

means detachably and adjustably connected to said secondary body element.
